UNITED STATES PATENT OFFICE.

OSCAR H. NEIMAN, OF FREEPORT, ILLINOIS.

LUBRICATOR.

984,839.

Specification of Letters Patent. Patented Feb. 21, 1911.

Application filed May 11, 1910. Serial No. 560,716.

To all whom it may concern:

Be it known that I, OSCAR H. NEIMAN, a citizen of the United States, residing at Freeport, in the county of Stephenson and State of Illinois, have invented certain new and useful Improvements in Lubricators; and I do hereby declare the following to be a full, clear, and exact description of the invention, such as will enable other skilled in 10 the art to which it appertains to make and use the same.

This invention relates to force feed lubricators provided with slidable pistons for ejecting grease; and it consists in the novel 15 construction and combination of the parts hereinafter fully described and claimed.

In the drawings, Figure 1 is a longitudinal section through the lubricator. Fig. 2 is a front end view of the lubricator. Fig. 20 3 is a detail view of the piston, partly in section. Fig. 4 is an interior view of the rear end of the lubricator.

A is a cylinder for holding the grease.

B is a conical cap or cover provided with 25 an annular groove *b* which fits over the front end of the cylinder A. A packing *b'* is placed in the groove for the end of the cylinder to bear against.

C are bolts pivoted by pins *c* to lugs *c'* on 30 the cylinder. These bolts are provided with thumb-nuts D and they pass through a hole *c* and a slot *c'* in lugs *c* which project from the cover B, and hold the cover tightly against the cylinder and so that it can easily 35 be removed to fill the cylinder with grease.

E is a spout which is screwed into the cover B.

F is a plate secured to the other end of 40 the cylinder from the cover, so as to close the cylinder, but without making it airtight. This plate is provided with a guide *f*.

G is a piston-rod formed of a screw which works in the guide *f*, and which is provided with an operating-handle or wheel *g* on its 45 end outside the cylinder.

H is a piston disk which is provided with a hub *h* which is journaled on a bearing *h'* at the other end of the piston-rod from its handle, between a shoulder *i* and a pin 50 or stop *i'*.

J is a cup-leather, *j* is a washer, and *j'* are bolts which secure the cup-leather and washer to the piston disk H.

K is a spring split ring arranged inside the cup-leather between its cylindrical portions

and the periphery of the disk, and which holds the cup-leather against the cylinder wall. This piston is specially constructed so that it is grease-tight and so that it will work freely and with as little friction as possible.

The plate F has a lever L pivoted to it at one end by a pin *m*, and a half-nut *m'* is formed on the middle part of this lever and is arranged to engage with the screw G, the guide *f* being cut away on one side to accommodate the half-nut.

N is a spring arranged between the free end portion of the lever L and a lug *n* on the plate F, and operating to move the half-nut out of engagement with the screw.

P is an eccentric pivoted to the plate F by a pin *p* and operating to hold the half-nut in engagement with the screw when placed in the position shown in Fig. 4.

The parts L, N and *n* are arranged on the inside face of the plate F, and the plate F has a hole *f* through which the sectional-nut *m'* is arranged to project so that it may work in the notch in the guide and be engaged by the eccentric P which is pivoted against the outside face of the plate F.

The grease is ejected from the cylinder by revolving the screw; and the cover is freed and swung around by removing one bolt and loosening the other bolt, to permit the cylinder to be refilled with grease. The half-nut is disengaged from the screw, to permit the piston to be drawn back quickly, by turning the eccentric out of engagement with the lever.

What I claim is:

1. In a lubricator, the combination, with a cylinder for grease, of a revoluble piston-rod provided with means for revolving it to force out the grease from the cylinder, and a non-revoluble piston journaled loose on one end portion of the piston-rod and comprising a disk, a cup-leather secured to the disk, and a spring split-ring which presses the cylindrical part of the cup-leather against the cylinder.

2. In a lubricator, the combination, with a cylinder for grease having a plate at one end provided with a cylindrical guide, said guide having a notch on one side and the said plate having a hole adjacent to the notch, of a screw threaded piston-rod slideable in the said guide, a piston operated by the said piston-rod, a lever pivoted against

2
the inner side of the said plate and provided
with a sectional-nut which is arranged in
the said notch and hole, an eccentric pivoted
against the outer side of the said plate and
5 operating to place the nut in engagement
with the piston-rod, and a spring for mov-
ing the lever in the reverse direction.

In testimony whereof I have affixed my
signature in the presence of two witnesses.

OSCAR H. NEIMAN.

Witnesses:

HENRY B. WITTE,

EDNA E. DITZLER.
